[57] CLAIM

The ornamental design for an electrical connector housing, as shown and described.

DESCRIPTION

FIG. 1 is a top plan view of an electrical connector housing showing our new design;

FIG. 2 is a front elevational view thereof;

FIG. 3 is a bottom plan view thereof;

FIG. 4 is a left side elevational view thereof;

FIG. 5 is a right side elevational view thereof;

FIG. 6 is a rear elevational view thereof;

FIG. 7 is a cross-sectional view thereof taken along line 7-7 of FIG. 2;

FIG. 8 is a cross-sectional view thereof taken along line 8-8 of FIG. 2;

FIG. 9 is a cross-sectional view thereof taken along line 9-9 of FIG. 2;

FIG. 10 is a cross-sectional view thereof taken along line 7-7 of FIG. 2 shown coupled with another connector housing. The broken line showing of the coupled housing is included for the purpose of illustrating environmental elements only and forms no part of the claimed design; and,

FIG. 11 is a perspective view thereof as seen from the rear and upper left.
